FLUID PRESSURE OPERATED VARIABLE
PITCH PROPELLERRobert J. Ruths, Baltimore, Md., and Harry L.
Dodson, United States Navy

Application August 10, 1938, Serial No. 224,667

1 Claim. (CL 170—163)

(Granted under the act of March 3, 1883, as
amended April 30, 1928; 370 O. G. 757)

This invention relates to variable pitch propellers and it has for its principal object the provision of a new and improved propeller of the character described in which the pitch of the several blades may be adjusted by hydraulic pressure operated means acting through the propeller shaft and hub while the same are in motion.

With these and other objects in view, as well as other advantages that may be incident to the use of the improvements, the invention consists in the parts and combinations thereof hereinafter set forth and claimed, with the understanding that the several necessary elements constituting the same may be varied in proportion and arrangement without departing from the nature and scope of the invention, as defined in the appended claim.

In order to make the invention more clearly understood, there are shown in the accompanying drawing means for carrying the invention into practical use, without limiting the improvements in their useful application to the particular construction which, for the purpose of explanation, have been made the subject of illustration.

In the accompanying drawing:

The single figure in the accompanying drawing is a diagrammatic view partly in side elevation and partly in longitudinal section of a propeller constructed in accordance with the invention.

Referring to the drawing, a variable pitch propeller embodying the invention is shown as comprising a hub 10 secured to a drive shaft 11 and having a plurality of circumferentially arranged sockets 12 formed therein, in each of which the root portion 13 of a blade 14 is mounted for rotation about a radial axis.

The hub is also formed with a chamber 15 of triangular cross-section in which a block 16 of similar shape is mounted for fore and aft sliding movement. Each face of the block 16 is formed with a transverse slot 17 in which a block 18 is slidably mounted and is engageable by an eccentrically disposed crank pin 19 fixed to the root 13 of the blade 14. The block 16 is reciprocated in order to swing the blades 14 about their axes of rotation by means of a rod 20 which is fixed to a piston 21 mounted in a cylinder 22 formed in the forward end of the hub. Fluid under pressure is supplied to the cylinder 22 in order to reciprocate the piston, through passageways 23 and 24 extending longitudinally through the hub 10 and shaft 11 which communicate with chambers 25 and 26, respectively, formed by cup-shaped members 27 on each side of a collar 28 provided on the

shaft 11. Leakage between the chambers 25 and 26 and past the collar 28 is prevented by packing 29 and from these chambers around the shaft by glands 30. Fluid under pressure is at times supplied to one or the other of the chambers 25 and 26 through pipes 31 and 32 through the medium of a suitable pump and valve mechanism, not shown.

In operation, when it is desired to alter the pitch of the blades 14 in one direction, fluid is forced into the right-hand end of the cylinder 22 through the pipe 31, chamber 25 and passageway 23, the fluid in the left-hand end of the cylinder escaping through the passageway 24, chamber 26 and pipe 32. If it is desired to alter the pitch of the blades in an opposite direction the flow of fluid under pressure is reversed.

The propeller blades 14 are of the balanced type, that is to say, the area of thrust on opposite sides of the radial axis about which they are adjustable, is equal so that the power required to turn the blade will be the same in either direction.

It will be understood that the above description and accompanying drawing comprehend only the general and preferred embodiment of the invention and that various changes in construction, proportion and arrangement of the parts may be made within the scope of the appended claim without sacrificing any of the advantages of the invention.

The invention described herein may be manufactured and used by or for the Government of the United States of America for governmental purposes without the payment of any royalties thereon or therefor.

We claim:

A variable pitch propeller comprising a shaft having a collar thereon and fluid pressure inlet and outlet passageways therein, a hub fixed to said shaft and having a fluid pressure cylinder formed therein communicating with said passageways, a piston in said cylinder, a blade mounted on said hub for rotation about a radially extending axis, means operatively connecting said piston with said blade whereby reciprocation of the former will rotate the latter about said axis, and a pair of cup-shaped members clamped together against opposite sides of said collar and forming therewith inlet and outlet chambers communicating with the passageways in said shaft and adapted to selectively supply fluid under pressure to said cylinder on opposite sides of said piston.

ROBERT J. RUTHS.

HARRY L. DODSON.
